UNITED STATES PATENT OFFICE.

HARRY FRANKLIN WATERS, OF BRATTLEBORO, VERMONT.

DESIGN FOR A PIPE ORGAN.

Application filed April 15, 1929. Serial No. 30,908. Term of patent 14 years.

To all whom it may concern:

Be it known that I, HARRY F. WATERS, a citizen of the United States of America, residing in Brattleboro, in the county of Windham, State of Vermont, have invented a new, original, and ornamental Design for a Pipe Organ, of which the following is a specification, reference being had to the accompanying drawing, forming a part thereof.

In the drawing, Fig. 1 is a perspective view of a pipe organ showing my new design, and Fig. 2 is a perspective view of the pipe organ shown in Fig. 1 but looking in the direction of the front of the pipe organ.

I claim:

The ornamental design for a pipe organ, as shown.

HARRY FRANKLIN WATERS.
